Primary Examiner — Karen E. Eldridge Powers*Assistant Examiner* — Kimberly Barnes(74) *Attorney, Agent, or Firm* — David O. Simmons(57) **CLAIM**

The ornamental design for a cap bill with wavy edge, as shown and described.

DESCRIPTION

FIG. 1 is a front perspective view of a cap bill with wavy edge in accordance with the present invention;

FIG. 2 is a top plan view of the cap bill with wavy edge shown in FIG. 1;

FIG. 3 is front elevation view of the cap bill with wavy edge shown in FIG. 1;

FIG. 4 is a left side elevation view of the cap bill with wavy edge shown in FIG. 1 wherein a right side elevation view of the cap bill with wavy edge shown in FIG. 1 is a mirror image of FIG. 4; and,

FIG. 5 is a bottom plan view of the cap bill with wavy edge shown in FIG. 1.

The broken lines showing a cap crown in FIGS. 1-5 depict environmental subject matter and form no part of the claimed design.

1 Claim, 3 Drawing Sheets(56)
